UNITED STATES PATENT OFFICE

2,440,537

EXCITER LAMP SUPPLY

Herbert Belar, Palmyra, N. J., assignor to Radio Corporation of America, a corporation of Delaware

Application October 31, 1942, Serial No. 464,131

3 Claims. (Cl. 315—179)

1

This invention relates to the current supply for an exciter lamp such as used with photoelectric apparatus and particularly to photoelectric apparatus of the sound reproducing type.

It is customary, in sound reproducers and analogous apparatus, to use an exciter lamp of the low voltage, high intensity type, for example, a 10 volt, 7½ ampere lamp is quite usual in sound reproducers and lamps of other voltages and currents of this general order are used. The average motion picture theatre is supplied with 110 volt, 60 cycle alternating current and if this current is stepped down by a transformer to operate the exciter lamp, a very noticeable 120 cycle hum will be produced in the sound reproducer, although the low voltage, heavy filament exciter lamps are not as bad in this respect as 110 volt lamps with a thinner filament. In order to avoid this hum, many expedients have heretofore been provided. Storage batteries have been used but the space occupied by such batteries and the expense of upkeep are quite considerable. High frequency current from an oscillator has been used on small exciter lamps but the cost of an oscillator and its proper power supply render this arrangement impractical for the large exciter lamps. Current for the exciter lamps has also been rectified and filtered and although this is an accepted commercial practice, the cost of the rectifier and filter is quite considerable. In inexpensive equipment it has been customary to use alternating current on the exciter lamp and to provide the amplifier or the sound reproducer or both with such characteristics that frequencies below about 150 cycles would not be reproduced at a high level. This, of course, eliminates the A.-C. hum but at the cost of the lower frequencies from the sound record.

It will be apparent that all the foregoing arrangements have their advantages and that each of them has certain disadvantages. In my improved construction, the high cost of either the oscillator, the storage battery or the rectifier is avoided. The circuit is much simplified and at the same time a result is produced which is comparable with that produced by a good rectifier and filter or a storage battery of reasonable size.

In my improved arrangement, I supply the exciter lamp with current through a device which will give a more or less flat topped characteristic to the current so that the filament current remains substantially constant during a considerable portion of each half cycle. If the flat topped portion of the current wave is a sufficiently large

2

percentage of the half cycle, the thermal inertia of the filament will tend to smooth out the interruption between that half cycle and the corresponding portion of the next half cycle and a substantially uniform illumination with very little hum producing characteristic will result.

One object of the invention is to provide an exciter lamp supply which will prevent hum in the sound reproducer.

10 Another object of the invention is to provide a relatively simple exciter lamp supply which will provide uniform current for the exciter lamp.

Another object of the invention is to provide means of controlling the current through the exciter lamp.

Other and incidental objects of the invention will be apparent to those skilled in the art from a reading of the following specification and an inspection of the accompanying drawing in

20 which:

Figure 1 is a diagrammatic illustration of my improved exciter lamp supply;

Figure 2 shows approximately the wave form of alternating current at a low voltage;

25 Figure 2 shows the wave form of alternating current at a high voltage;

Figure 3 shows the wave form of the current of Fig. 2 after it has been modified by my apparatus;

30 Figure 3A shows the wave form of the current of Fig. 2A after it has been modified by my apparatus;

Figure 4 shows the filament temperature produced by current of the form shown in Fig. 3; and

35 Figure 4A shows the filament temperature curve produced by current of the form shown in Fig. 3A.

Referring first to Fig. 1, the alternating current is supplied to the exciter lamp 10 having a filament 11 through a control lamp 12. The control lamp 12 is provided with relatively heavy leads 13 and with a plurality of relatively fine filaments 14. The filaments 14 preferably operate at a rather high temperature in vacuum so that the thermal emission from the filaments will follow the radiation laws in their temperature variation. With the usual types of resistance lamps, the filaments operate at a relatively low temperature in a thermally highly conductive atmosphere, such as hydrogen. This type of resistance lamp 12 does not tend to change its losses as rapidly with change in current as the vacuum type above referred to. Any type of resistance or current control device may be used which effectively limits the current to a constant value and the greater 45 the voltage drop in the current control device,

the more nearly the current will become constant. As indicated in Fig. 3, if the voltage drop across the resistance device 14 is relatively low, the current waves will have flat tops but very rounded corners, while if the voltage drop is greater than as indicated in Fig. 3A, the wave shape will become substantially square with very slightly rounded corners.

Although the current reverses in direction each half cycle, this reversal does not itself affect the filament temperature. As shown in Fig. 4, when a current of the shape indicated in Fig. 3 is used, the filament temperature will remain substantially constant with a slight drop between the half cycles due to the rounded corners of the wave shape.

If a larger voltage drop occurs in the control device 14, then the filament temperature will follow the curves shown in Fig. 4A where the drop in current is quite abrupt but the filament temperature as indicated by the dotted line changes only very slightly during the period of the rounded corners of the wave shape.

In order to secure maximum reduction of hum it is desirable, for the reasons just given, to secure a maximum of voltage drop in the device 14 in proportion to the voltage drop in the exciter lamp filament 11. For example, the apparatus may be connected across the 110 volt supply line and if, for example a 10 volt exciter lamp is used, then the resistance device would be designed to pass the current required by the lamp and to provide a voltage drop of 100 volts. This arrangement provides a very square wave shape and practically completely eliminates any hum due to the exciter lamp as this hum would be brought down to a level below the normal hum level of the amplifier.

In choosing the proper voltage to be applied and the voltage drop to be absorbed in the device 14, a number of factors should be considered, such as power loss as compared with the reduction of hum and the amount of hum reduction necessary in order to produce satisfactory results with the particular amplifier and sound reproducer used. It would be unnecessary to reduce the hum materially below the hum produced by the amplifier and hum reduction below this level would be uneconomical as it would increase the cost of the current control device and increase the power loss.

It will be apparent to those skilled in the art that the current control device does not need to be of the type shown and described as vacuum tube circuits are available for controlling current which will accomplish substantially the same result. The form of the invention shown, however, is at present the preferred form due to the commercial lack of vacuum tubes of sufficient size

and number to satisfactorily control commercial exciter lamps and due to the relatively greater cost of such tubes if available.

I claim as my invention:

5 1. A photoelectric sound reproducing system, including the combination of an exciter lamp, terminal connections to a source of alternating voltage for said lamp, and a resistor of low thermal inertia connected in series between said lamp and said terminal connections and having a resistance which varies with the amplitude of said voltage during a period which is small in relation to a half cycle of said voltage.

10 15 2. A system according to claim 1 wherein said resistor is contained in an evacuated envelope and comprises a plurality of conductors of high resistance connected in parallel with each other.

15 20 3. A photoelectric sound reproducing system, including the combination of an exciter lamp, terminal connections to a source of alternating current for said lamp, and means of low thermal inertia connected in series between said lamp and said terminal connections for converting each successive half cycle of said current to a wave 25 of substantially rectangular shape.
